CLAIM

I claim the ornamental design for a tire sealing and inflation device, as shown and described.

DESCRIPTION

FIG. 1 is a top perspective view of a tire sealing and inflation device showing my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The present application relates to a tire sealing and inflation device in which the broken line shown is for the purpose of illustrating portions which forms no part of the claimed design.
